UNITED STATES PATENT OFFICE.

EDWARD P. BATES, OF SYRACUSE, NEW YORK.

FIRE-POT FOR BOILERS.

SPECIFICATION forming part of Letters Patent No. 273,012, dated February 27, 1883.

Application filed September 6, 1882. (No model.)

To all whom it may concern:

Be it known that I, EDWARD P. BATES, of Syracuse, in the county of Onondaga and State of New York, have invented a certain new and 5 useful Improvement in Fire-Pots for Boilers, of which the following is a specification.

My improvement relates particularly to steam-boilers, such as are used in houses and other buildings for generating steam for heating apparatus.

The improvement consists in the combination, in a steam-boiler, of a water-chamber, a fire-pot, flues extending from the upper part of the fire-pot through the water-chamber, and 15 serving to conduct heat and to carry waste products of combustion from the fire-pot, an outer casing surrounding the fire-pot and water-chamber, and a number of coal-feeders extending downwardly at angles from the exterior of the outer casing to opposite portions of 20 the fire-pot, so as to deliver fuel around the fire-pot, the wall of the fire-pot being closed entirely around except where the coal-feeders open into it. I also preferably combine with 25 the above an automatic draft or damper regulator.

The invention also consists in a novel combination of parts hereinafter described.

In the accompanying drawings, Figure 1 is 30 an outside view of a steam-boiler embodying my improvement. Fig. 2 is a central vertical section of the same, and Fig. 3 is a horizontal section thereof.

Similar letters of reference designate corresponding parts in all the figures.

A designates a fire-pot, preferably made of wrought-iron. It is of a proper height to contain a deep and slow-burning fire, and to form a combustion-chamber wherein combustible 40 gases may be ignited before the products of combustion enter the flues B, which surmount it.

The shell or water space or chamber C of the boiler extends down around the fire-pot and up to the top of the flues.

45 The grate D is composed of a number of rocking bars. The ash-pit is of ordinary form. Outside the shell of the boiler is a heat-chamber, E, formed in the masonry M of the boiler. The masonry forms an outer casing for the 50 boiler. The products of combustion escape

into this heat-chamber from the flues B. The heat-chamber has a removable cover, E', for facilitating cleaning. From this heat-chamber the products of combustion pass into a flue, F, whereby they are carried off. The steam generated in the boiler is conveyed away by a suitable pipe. 55

The boiler is furnished with a water-gage, H, a blow-off pipe and cock, I, and an open tube extending from the shell of the boiler 60 just below the normal water-level, and affording a relief to the boiler upon the accumulation of excessive pressure in it. This tube must extend to a height corresponding to the pressure to be maintained in the boiler. 65

J designates an automatic water-feeder for maintaining the proper level of water.

K designates an automatic draft-regulator, which is actuated by the pressure of steam in the boiler to shift the ash-pit door L for varying the draft. 70

N designates the coal-feeders. They consist of spouts made of cast-iron or other suitable material, and extend through the side of the masonry and shell of the boiler to the fire-pot. They are arranged at opposite points, and are here shown as four in number. They 75 are filled with coal, and as the fire needs more coal it is automatically supplied. The coal is delivered by these feeders to the sides of the 80 fire-pot. These feeders also serve the purpose of air-reservoirs, and as they nearly encircle the fire they conduct air to almost all parts of the fire.

If it is desirable to feed from only two or 85 three sides of the boiler, I may employ, in conjunction with the feeders N, one or more branch feeders or chutes, O, extending from a side or sides to a feeder or feeders, N, located in an adjacent side or sides. 90

It will be observed that the feeders N are of great width in proportion to their depth, and that where a number are arranged at opposite points they deliver coal around almost the entire circumference of the fire-pot, as is shown 95 most clearly in Fig. 3. The fire-pot is closed entirely around except where the feeders enter it. The automatic draft-regulator and the inclined coal-feeders coact to maintain a uniform pressure of steam or degree of heat in the 100

boiler and a uniform fire in the fire-pot, and when provided with both the automatic draft-regulator and the coal-feeders a boiler will need very little attention.

5 What I claim as my invention, and desire to secure by Letters Patent, is—

1. In a steam-boiler, the combination of a water-chamber, a fire-pot, flues extending from the upper part of the fire-pot through the water-chamber, and serving to conduct heat and

to carry the waste products of combustion from the fire-pot, an outer casing surrounding the fire-pot and water-chamber, and a number of coal-feeders extending downwardly at angles 15 from the exterior of the casing to opposite portions of the fire-pot, so as to deliver fuel around the fire-pot, the wall of the fire-pot being closed entirely around except where the coal-feeders open into it, substantially as specified.

20 2. In a steam-boiler, the combination of a water-chamber, a fire-pot, flues extending from the upper part of the fire-pot through the water-chamber, and serving to conduct heat and to carry the waste products of combustion from

the fire-pot, an outer casing surrounding the fire-pot and water-chamber, a number of coal-feeders extending downwardly at angles from the exterior of the casing to opposite portions of the fire-pot, so as to deliver fuel around the fire-pot, the wall of the fire-pot being closed 30 entirely around except where the coal-feeders open into it, and an automatic draft-regulator for controlling the admission of air, substantially as specified.

3. In a steam-boiler, the combination of the water-chamber C, the fire-pot A, flues B, leading from the upper part of the fire-pot through the water chamber, a number of coal-feeders, N, extending laterally at inclines to opposite parts of the fire-pot and serving to supply coal 40 around the outer part of the fire-pot, and a branch feeder, O, extending transversely to one of the feeders N and adjacent to another of said feeders, substantially as specified.

EDWARD P. BATES.
